PRESS-BUTTON.

1,128,341.

Specification of Letters Patent. Patented Feb. 16, 1915.

Application filed May 21, 1912. Serial No. 698,830.

REISSUED

To all whom it may concern:

Be it known that I, ALFRED MANN, residing at Schützenstrasse 51, Barmen, Rhenish Prussia, Germany, a subject of the Emperor of Germany, have invented new and useful Improvements in Press-Buttons, of which the following is a specification.

This invention relates to improvements in press-buttons and particularly to that 10 class of buttons in which the cap of the female member is provided with an outer spring which reaching into the interior of the cap holds the male member or stud in its closed position. As is well known these 15 buttons have the draw-back that they easily spring open when attached to blouses or like clothing and when a lateral pull is exerted thereon. To overcome this disadvantage I have constructed the cap and stud in 20 such a manner that both have a ball like shape, that one fits closely in the other and that the cap presents a support for the stud, which jams against said support when exposed to lateral pull so that no springing 25 open of the button can take place. With these arrangements in view my invention is shown on the accompanying drawing in an enlarged scale on which—

Figure 1 is a vertical section of the complete button. Fig. 2 is a top view and Fig. 3 is a vertical section showing the operation of the button when exposed to lateral pull or traction.

Like letters of reference indicate like 35 parts in the drawings.

Referring to the drawings the button consists of a plate *a* on which is formed the cap *b*. This cap is of particular shape as seen in the drawings, it is made ball like 40 forming in its interior a shoulder or the like *s*.

c is the usual wire spring which may be made of one piece as shown or of two separate pieces and clamped to the plate by

means of the rim, its shanks *c*¹ engage recesses in the cap as shown in Figs. 1 and 2.

d is the plate of the male member which is provided with the stud *e*. This stud is not made cylindrical as usually but has a ball like shape and is of such a diameter so as 50 to closely fit the entrance in the cap member as shown by the dotted lines in Fig. 1.

My new button has the advantage, that it can be opened only when drawn asunder in axial direction as shown by the arrow. Any 55 other lateral pull or traction will not separate the members. In such a case Fig. 3, the head *e* bears against the supports *s* and the rim or edge *d*¹ bears against the plate *a* and it is therefore quite impossible to open the button. It may be mentioned that in my button the spring may be made not so strong as in ordinary buttons in which said spring shall prevent the self-opening of the button.

What I claim is:—

A separable fastener comprising a plate having an annular substantially tubular flanged member extending upwardly therefrom, a central cap, said cap having an enlarged portion and a contracted portion forming shoulders adjacent the plate, said shoulders having cut out portions, a spring member having curved portions terminating in relatively straight portions, the curved 70 portions providing resiliency to the spring, and the straight portions being positioned in the cut out portions of the shoulders whereby a portion of the spring extends beyond the shoulders, a member carrying a stud, 75 said stud adapted to be positioned in the cap and the outer walls of the stud adapted to engage the straight portions of the spring, substantially as described.

ALFRED MANN. [L.S.]
